(57) **CLAIM**

The ornamental design for a display screen or portion thereof with transitional graphical user interface, as shown and described.

DESCRIPTION

The file of any patent that grants from the present application contains at least one drawing/photograph executed in color. Copies of any patent that grants from the present application with color drawing(s)/photograph(s) will be provided by the Office upon request and payment of the necessary fee.

FIG. 1 is a front view of a display screen or portion thereof with transitional graphical user interface showing our new design; and,

FIG. 2 is a front view of a second image thereof.

The appearance of the image transitions sequentially between the images shown in FIGS. 1-2. The process or period in which one images transitions to another forms no part of the claimed design.

The outermost dot-dash broken lines in FIGS. 1-2 show a display screen or portion thereof, and form no part of the claimed design.
